UNITED STATES PATENT OFFICE.

WILLIAM S. MOYER, OF PHILADELPHIA, PENNSYLVANIA.

ICE-CUTTING MACHINERY.

SPECIFICATION forming part of Letters Patent No. 325,183, dated August 25, 1885

Application filed October 6, 1884. (No model.)

To all whom it may concern:

Be it known that I, WILLIAM S. MOYER, of the city and county of Philadelphia, and State of Pennsylvania, have invented a new and 5 useful Improvement in Ice-Cutting Machinery, of which the following is a specification.

My invention has reference to ice-cutting machinery adapted to cutting large surfaces of ice into cakes; and it consists in certain improvements, fully set forth in the following specification and shown in the accompanying drawings, which form part thereof.

The object of my invention is to provide a suitable frame capable of being raised or lowered and driven backward or forward by suitable gearing, which also rotates a circular saw or cutter carried by said frame, to the end that said saw may cut partly or wholly through the ice, as desired, forming long narrow 20 grooves, which separate the cakes. I provide a machine which is capable of being operated wholly by hand-power, compact and durable in construction, and capable of being perfectly controlled by the operator.

25 In the drawings, Figure 1 is a side elevation of my improved ice-cutting machine. Fig. 2 is a plan view of same. Fig. 3 is an end elevation of same, and Fig. 4 is a skeleton view representing the mechanism by which the 30 machine may be driven forward or backward or adjusted vertically.

A represents the main frame of the machine, which is supported at one end upon rollers or wheels B, secured thereto upon an axle, b', and 35 at the other end by an adjustable frame, C, provided on its bottom with rollers or wheels B'. These wheels B and B' are provided with teeth b, which catch upon the ice and insure the machine being fed horizontally and run 40 true; but, if desired, the said wheels B' may be without teeth b.

E is the circular saw or cutter, and is firmly secured to the shaft E', supported by said frame A, and rapidly rotated through the 45 agency of the gears F, F', F², and F³, shaft f, and crank f', and one or more of the shafts supporting said gears may be provided with fly-wheels G, and to operate said crank the operator stands upon the platforms e', carried 50 by the frame A, and the upper portion of the saw is protected by a casing, e, carried by one of said platforms e'. The drive-wheels B and

their shaft b' are rotated forward through the agency of the chain L, which passes about a sprocket-wheel, M, secured to the shaft b', and 55 backward through the agency of the chain P and sprocket-wheel P'. The chain L passes around the sprocket-wheel K, loosely supported upon a shaft, H, which is rotated through the agency of said gears G, G', G², 60 and G³, and receives its motion from the crank-shaft f.

K' is a double clutch, which is rotated with said shaft H, and may be longitudinally shifted upon its shaft to mesh with teeth upon either 65 of the sprocket-wheels K and I through the agency of a hand-lever, k.

To rotate the shaft b' in the opposite direction, the chain P passes over a sprocket-wheel, O², which is secured upon a shaft, O³, receiving 70 its motion from shaft H through the agency of gears O and O', the said shafts H and O³ rotating in opposite directions. The sprocket-wheel O² is loosely supported upon shaft O³, and may be put in or out of motion by a double 75 clutch, R, carried by said shaft O³, and adapted to be shifted longitudinally upon the same to catch with the sprocket-wheel O² or I' by means of a hand-lever, R'.

The frame C is provided with a rack, C', into 80 which meshes the main gear D, supported upon a shaft journaled on frame A and secured to sprocket-wheels D' and D², around which chains J and J' pass, respectively, to the sprocket-wheels I' and I, hereinbefore referred to. 85 By throwing the clutch K' into contact with the sprocket-wheel I the frame A is caused to mount the frame C, as indicated in Fig. 1, the latter frame being guided in a suitable manner by the former, allowing of vertical adjustment. If, however, the clutch R be thrown into contact with the sprocket-wheel I', then the frame A is lowered upon the frame C. By 90 this means the saw may be made to cut any depth desired, and the depth cut may be varied at will. After raising the frame A to any desired height it may be retained in position by means of pins W, which enter holes W' in the frame C, and upon which pins the frame A rests. The frame C is provided with a cam-surface, C², so arranged that when the frame A is fully raised the upper part of the same 95 will strike the end n of the pivoted lever N and cause the same to be moved, which actuates 100

the hand-lever k and throws the clutch K' out of contact with the sprocket-wheel I , preventing further raising of the frame A , and the cross-piece T' of the frame A is adapted to be caught upon the spring-catch T , secured to the frame C , and thus hold the frame A suspended at the full height which is necessary in conveying the machine from one place to another, and when the saw must not come in contact with anything. After moving to the proper position, the hand-lever R' is moved in such a manner as to move the lever S , which rests against it, and throw the clutch R into contact with the sprocket-wheel I' . This action simultaneously rotates the gear D , allowing the frame A to become lowered, and the hand-lever S presses upon the pawl S' , causing its free end to press the spring-catch T from under the cross-piece T' and allow the frame A to slowly descend with the speed commensurate with the rotation of the shaft O^3 , and as the frame descends the saw E cuts into the ice, and when the proper depth of cut is obtained the lever k may be shifted, to cause the shaft b' to rotate and drive the machine forward, enabling it to cut the grooves V in the ice. After cutting one groove the pointer or pointers U enable the operator to guide the machine to insure a uniform width of cake being cut, as indicated in Fig. 3. After making the incisions V in one direction the machine may be run at right angles to those first made, and the ice so cut can be rapidly and uniformly broken into cakes and stored in the ice-house. If desired, the saw may be made to completely cut through the ice. The cam C^2 may be made adjustable by removable or adjustable pieces C^3 , which will act sooner upon the end n of the lever N . While I prefer the construction set forth and illustrated, I do not limit myself to the details, as they may be modified in various ways without departing from my invention. Having now described my invention, what I claim as new, and desire to secure by Letters Patent, is—

1. In a machine for cutting ice, a frame carrying a rotary cutter, in combination with geared hand-power, substantially as set forth, for propelling said frame, a support for one end of the cutter-frame, provided with a rack, and a gear to mesh with said rack carried by the cutter-frame, and by which it may be adjusted vertically, the said gear being automatically operated by the motive power of the machine, substantially as and for the purpose specified.

2. In an ice-cutting machine, a frame supported upon the ice, in combination with a rotary cutter, a support for one end of the cutter-frame, and upon which it is adjustable vertically for raising or lowering the cutter relative to the ice, a rack and gear respectively carried by said frame, and by which they are adjusted, and connecting-gearing by which the same motive power being used for rotating and raising the cutter actuates the rack and gear, substantially as and for the purpose specified.

3. An ice-cutting machine consisting of a main frame supported upon wheels and arranged to be moved over the ice, in combination with a rotary cutter carried thereby and a frame upon which the main frame is vertically adjustable, gear and rack mechanism for adjusting said frames relatively to each other, by which the entire cutting machinery may be raised or lowered, substantially as and for the purpose specified.

4. In an ice-cutting machine, the frames A and C , in combination with rack C' , gear D , sprocket-wheels D' D^2 , chains J J' , and suitable devices, substantially as set forth, to put either of said chains into action to rotate said gear in either direction, as desired, to raise or lower the frame A , substantially as and for the purpose specified.

5. The combination of frame A , carrying cutter E , frame C , having rack C' , gear D , sprocket-wheels D' , D^2 , I , I' , O^2 , P' , K , and M , shafts H O^3 , clutches K' R , wheels B , and suitable gearing to rotate said shafts H and O^3 , substantially as and for the purpose specified.

6. The combination of frame A , carrying cutter E , frame C , having rack C' , gear D , sprocket-wheels D , D' , I , I' , O^2 , P' , K , and M , shafts H O^3 , clutches K' R , wheels B , and suitable gearing to rotate said shafts H and O^3 , catch T T' , pawl S' , levers R' , k , N , and S , and cam C^2 , substantially as and for the purpose specified.

7. The combination of frame A and frame C , adapted for adjustment, supporting-wheels B B' , and pins W , to support the frames A a given distance from the ground, substantially as and for the purpose specified.

In testimony of which invention I hereunto set my hand.

WILLIAM S. MOYER.
